UNITED STATES PATENT OFFICE.

WILLIAM E. WORTHEN, OF NEW YORK, N. Y.

IMPROVEMENT IN ROTARY VALVES.

Specification forming part of Letters Patent No. **56,657**, dated July 24, 1866.

To all whom it may concern:

Be it known that I, WILLIAM E. WORTHEN, of the city, county, and State of New York, have invented a new and useful Rotary Valve and Cut-Off applicable to Steam, Water, and Gas Engines; and I do hereby declare that the following, taken in connection with the drawings, is a full, clear, and exact description thereof.

In the drawings, Figure 1 is an elevation of the valve and valve-chest and part of the side pipe and cylinder. Fig. 2 is a longitudinal section through the same. Fig. 3 is a section at right angles to the former through the valve-chest, exhibiting the cut-off ring, the valve-seat, and the screw for adjusting the cut-off. Fig. 4 is a section through the cut-off ring, and through the apertures therein. Fig. 5 is an elevation of the ring.

This valve, as shown in the drawings, acts to admit steam to and permit the escape of steam from both ends of a cylinder, but by suppressing one opening or port in the seat is applicable to one end of a cylinder only, and it rotates upon a flat or nearly flat seat, the rotation being effected by a pitch-chain, cog-gearing, or any other suitable mechanical devices.

In the drawings a portion of a cylinder is shown at *a a a*, portions of side pipes at *b b*, the valve-chest at *c c*, and the ports at *d d* in the valve-seat *e e*.

The upper part of the valve-chest is bored out cylindrically, as at *f f*, Fig. 2, and I prefer to bore it cylindrically throughout, although that part forming the steam-passage *g g* may be of any proper form.

The steam-passage *g g* is of greater diameter than the upper part of the chest and extends round the chest. Steam is admitted from a generator, or water from a pipe at *h* passes into the passage, thence to the cavity of the valve, and thence to the ports.

The valve *h' h'* is cylindrical, and has two distinct cavities formed in it. One of them, *h²*, extends from the face to the back of the valve. The other, *h³*, extends from the face through that part of the periphery of the valve which is opposite the steam-passage. The openings in these cavities may be of any proper form. I prefer to make both openings in the

valve-face of the same form and dimensions as the ports *d d'*. The valve is packed to the valve-chest either by a gland and stuffing-box or in other proper manner. A ring or hoop, *k k*, fits closely around the lower periphery of the valve. I prefer to bore this ring a little smaller than the valve, to slit it and grind it to the valve. In this ring are two passages, *k' k²*, and the ring is prevented from turning with the valve by means of a rack upon the ring and a screw, *m*. The position of the openings *k' k²* can be varied with respect to the ports by means of this screw. As the steam enters this valve at the periphery instead of at the back, as in other rotating valves, the pressure within the cavity through which the steam passes to enter the cylinder will tend to lift the valve off its seat, and the friction is transferred from the seat to the appliances which hold the valve in contact with the seat. Consequently the wear of the face of the valve and of the seat is small, the valve remains tight for a longer period, and is more easily moved.

The appliances for confining the valve to its seat are a yoke, *n*, and a screw, *o*, which latter bears upon a pipe, *p*, that rests upon the back of the valve. This pipe is the escape-pipe, and does not revolve with the valve.

A flange or screw bearing directly upon the back of the valve, or any other proper instrumentality for holding it down upon the seat, may be substituted for those devices shown in the drawing, and any proper device for holding and moving the cut-off ring *k* may be substituted for the screw and rack.

The action of the valve when revolved is as follows: Steam enters through the aperture *h* into the passage *g*, thence through one of the openings *k' k²* into the opening in the cavity *h³*, and thence through the port that may be under that cavity, through the side pipe connecting therewith, and into the cylinder. Escape-steam passes out through the side pipe, through one of the ports into the cavity *h² h²*, and through the exhaust-pipe *p*. As the valve revolves steam will enter the cavity *h³* as long as the aperture therein at the periphery or any part thereof is opposite any part of either of the openings *k' k²*, and will pass from the cavity either by pressure or expansion as long as

any part of the opening in the face of the valve is over either of the ports d d' ; and the angular position of the valve with respect to the position of the piston in the cylinder and the size of the cavities in the valve-face, as also the size of the ports, must be so adjusted as to give such leads in steam and exhaust and such amount of fixed cut-off as may be desirable, and it is evident that the valve will work properly, either as a full-stroke valve or as a valve cutting off at a fixed and non-adjustable point, without the cut-off ring.

By altering the position of the cut-off ring the admission of steam into the steam-cavity of the valve may be stopped before the opening of that cavity in the valve-face leaves the port that may happen to be below it. The turning of the screw will therefore adjust the point of cut-off.

I claim as of my own invention—

1. A rotating steam-valve provided with a cavity extending from the periphery to the face

of the valve, as described, in combination with a seat, substantially such as described, and proper appliances, as specified, for holding the valve on its seat.

2. A rotating valve provided with two cavities, substantially such as described, in combination with proper appliances for holding the valve on its seat, a valve-seat, and a chest provided with a steam-passage, all substantially such as described, and all operating in combination, as set forth.

3. In combination with a rotating valve and a steam-passage, an adjustable cut-off ring, the combination being substantially such as specified and acting substantially as set forth.

In testimony whereof I have hereunto subscribed my name.

W. E. WORTHEN.

In presence of—

JOHN AVERY,
ENG. LEBEUF.
